BENJAMIN F. MIESSNER, OF SHORT HILLS, NEW JERSEY, ASSIGNOR, BY MESNE ASSIGNMENTS, TO RADIO CORPORATION OF AMERICA, OF NEW YORK, N. Y., A CORPORATION OF DELAWARE

AMPLIFIER ENERGIZING SYSTEM

Application filed July 20, 1929. Serial No. 379,673.

This invention relates in general to amplifier energizing systems, such as systems for energizing radio receivers constructed as units to be installed in cabinets and like housings utilized as receivers of present-day broadcast programs.

In particular, this invention relates to the energizing of an amplifier system, such as a radio receiver, in which the elements are mounted upon a chassis, and in particular those adapted to be energized from a commercial source of alternating current.

In alternating current energized types of receivers I have found that although such precautions have been taken as mounting the alternating current energy supply transformer at one end of the chassis while mounting the audio transformers of the system at the opposite end of the chassis, and so orientating the audio transformer with respect to the supply transformer that their fields are at right angles to each other, there is sufficient flux induced in the audio frequency transformers by the flux from the supply transformer that there results an appreciable hum in the output device of the system, such as a loud speaker.

I have found the inability to eliminate this hum by spacing and orientation of elements to be due to what seems to be a distortion of the flux field of the supply transformer by the usual metallic chassis upon which the various elements are mounted, so that there results a coupling between the supply transformer and the audio frequency transformers irrespective of all practical precautions to eliminate coupling by location and orientation of elements.

It is, therefore, the object of my invention to neutralize this coupling between the supply transformer and the audio frequency transformers, customary in the usual amplifying and radio receiver systems.

Further objects will become apparent as the description of the accompanying drawing is developed, in which there is diagrammatically shown a chassis, a supply transformer with its associated rectifier and filter system, an audio transformer, a number of vacuum

tubes, and an output transformer coupled to an indicator.

Referring particularly to the drawing, the chassis, indicated by the legend on the drawing, may be of any shape, either solid or latticed, upon which is mounted an alternating current energy supply transformer ST, the primary of which is provided with a pair of leads 1 and 2 adapted to be connected to a source of commercial alternating current supply, such as a house lighting system. The secondary of this transformer is provided with a plurality of secondaries S₁, S₂ and S₃, the particular number of which varies with the various types of receivers. I have shown the secondary S₁ as supplying energy to the anodes of a full wave rectifier tube RT, the filament of which is supplied with heating current from the secondary S₂, the output terminals of the rectifier, namely the center tap potentiometer CT₁ and the mid point of the secondary S₁, being shunted by the usual filter system indicated at FS.

VT indicates a plurality of amplifier tubes, the filaments of which are supplied with heating current by the secondary S₃ of the supply transformer ST. The space current of the tubes VT is supplied from the filter system FS by a connection from one terminal thereof to the plates of the tubes VT through a potential regulating device, such as R, and by a connection from the other terminal of the filter system FS through a grid biasing resistance GBR to a center tap potentiometer CT₂, which shunts the filaments of the tubes VT.

Reference character T designates one or a plurality of audio frequency transformers of the usual amplifier system, and in my preferred manner of use of my invention is the first audio frequency transformer of a cascaded amplifier system, the primary AP of which is supplied with audio frequency currents from the usual detector system following a series of cascaded radio frequency amplifier systems. I have shown the secondary AS as connected between the grid of tube VT and a point in the resistance GBR, whereby the proper grid potential of the tube

VT is maintained by the average plate current thereof.

I have shown the plate circuit of tube VT as including the primary of an output transformer OT, the secondary of which is coupled to a loud speaker LS, but it is to be understood that various arrangements may be substituted for the amplifier diagram shown herein, since these in no way form a part 10 of my present invention. As shown, the transformer T, preferably the first audio transformer of an amplifier system, is orientated with respect to the supply transformer ST so that the fields thereof, with respect to 15 the air path, are at substantially right angles to each other. This arrangement is preferable, since direct coupling between the transformers T and ST is reduced to a minimum, and only the stray field induced in the transformer T by the flux flowing through the 20 chassis requires neutralization.

This stray field I may neutralize by either one of two systems, first by connecting a coil L₁, having substantially identical flux characteristics as the stray field of supply transformer ST, in series in the filament circuits of tubes VT. By the proper orientation of the coil L₁ with respect to the transformer T, I have found that it is possible to neutralize 25 all the flux induced in the transformer T by the stray field of the transformer ST flowing through the chassis. Another arrangement consists in connecting a coil L₂ similar to the coil L₁ across a primary of the transformer ST and orienting this coil with respect to the transformer T so that any residual coupling existing between the transformers T and ST will be neutralized, the current flowing through the coil L₂ being 30 regulated by a resistance R₂ in series therewith.

Since any number of stages may be used in the audio frequency amplifier system of a commercial radio broadcast receiver, I do 45 not wish to be limited to the use of but one coil L₁ or one coil L₂ coupled to the first audio transformer, but may couple such coils either singly or in combination with the several audio frequency transformers of such 50 a cascaded amplifier system without departing from the spirit of my invention.

It is to be further understood that the series connection of the coil L₁ in the filament circuit of the rectifier RT is within the contemplated scope of my invention in the following claims, wherein the coil L₁ is defined to be within the filament heating circuit of the tubes of the radio receiver.

Having described my invention what I 60 claim is:

1. In an amplifying system the combination of a chassis, an alternating current energy supply transformer mounted upon said chassis, an audio frequency transformer forming part of an amplifying system carried

by said chassis, and means operatively associated with said supply transformer and in close proximity to said audio transformer for neutralizing the flux induced in said audio transformer by flux flowing through said 70 chassis from said supply transformer.

2. In an amplifying system, the combination of a chassis, an alternating current energy supply transformer mounted upon said chassis, an audio frequency transformer forming part of an amplifying system carried by said chassis, and means in close proximity to said audio transformer for neutralizing the fluctuating field coupling between said supply transformer and said audio transformer, said means consisting of a coil energized from one of the windings of said supply transformer and so orientated with respect thereto that the flux induced in said audio transformer by the flux of said 80 supply transformer is opposed by the flux from said coil.

3. In an amplifying system, the combination of a chassis, an alternating current energy supply transformer mounted upon said chassis, an audio frequency transformer forming part of an amplifying system carried by said chassis, and means in close proximity to said audio transformer for neutralizing the fluctuating field coupling between said supply transformer and said audio transformer, said means consisting of a coil having substantially the same flux variation characteristics as said supply transformer.

4. In an amplifying system, the combination of a chassis, an alternating current energy supply transformer mounted on said chassis, an audio frequency transformer forming part of an amplifying system carried by said chassis, said supply transformer and said audio transformer having the axes of their windings at substantially right angles to each other whereby the air path of the flux of said supply transformer upon said 100 audio transformer is reduced to a minimum, and means in close proximity to said audio transformer for neutralizing the flux induced in said audio transformer by flux flowing through said chassis from said supply transformer.

5. In an amplifying system, the combination of a chassis, an alternating current energy supply transformer mounted on said chassis, an audio frequency transformer forming a part of an amplifying system carried by said chassis, said supply transformer and said audio transformer having the axes of their windings at substantially right angles to each other whereby the air path of the flux of said supply transformer upon said audio transformer is reduced to a minimum, and means in close proximity to said audio transformer for neutralizing the flux induced in said audio transformer by flux flowing 110

- through said chassis from said supply transformer, said means consisting of a coil energized from one of the windings of said supply transformer and so orientated with respect to said audio transformer that the flux induced in said audio transformer by the flux flowing through said chassis is opposed by the flux from said coil.
6. In an amplifying system, the combination of a chassis, an alternating current energy supply transformer mounted on said chassis, an audio frequency transformer forming a part of an amplifying system carried by said chassis, said transformer and said audio transformer having the axes of their windings at substantially right angles to each other whereby the air path of the flux of said supply transformer upon said audio transformer is reduced to a minimum, and means in close proximity to said audio transformer for neutralizing the flux induced in said audio transformer by flux flowing through said chassis from said supply transformer, said means consisting of a coil having substantially the same flux variation characteristics as said supply transformer.
7. In a radio receiver unit, the combination of a chassis, an alternating current energy supply transformer mounted on said chassis, a plurality of vacuum tubes and associated circuits carried by said chassis and forming a radio receiver including an audio frequency amplifying system including an audio frequency transformer, and means coupled to one of the energizing circuits of said tubes and positioned in close proximity to said amplifier for neutralizing the fluctuating field coupling between said supply transformer and said audio transformer.
8. In a radio receiver unit, the combination of a chassis, an alternating current energy supply transformer mounted on said chassis, a plurality of vacuum tubes and associated circuits carried by said chassis and forming a radio receiver including an audio frequency amplifying system including an audio frequency transformer, and means, including a coil coupled to one of the energizing circuits of said tubes, located in close proximity to said audio transformer, so orientated with respect thereto that the flux induced in said audio transformer by the flux of said supply transformer is neutralized by the flux from said coil.
9. In a radio receiver unit, the combination of a chassis, an alternating current energy supply transformer mounted on said chassis, a plurality of vacuum tubes and associated circuits carried by said chassis and forming a radio receiver including an audio frequency amplifying system, including an audio frequency transformer, and means, including a coil having substantially the same flux variation characteristics as said supply transformer, coupled to one of the energizing
- circuits of said tubes and located in close proximity to said amplifying transformer, so orientated with respect thereto that the flux induced in said audio transformer by the flux of said supply transformer is neutralized by the flux from said coil.
10. In a radio receiver unit, the combination of a chassis, an alternating current energy supply transformer mounted on said chassis, a plurality of vacuum tubes and associated circuits carried by said chassis and forming a radio receiver including an audio frequency amplifying system, including an audio frequency transformer, and a coil series related in the filament heating circuit of at least one of said tubes and located in close proximity to said audio transformer with an orientation with respect to said audio transformer by which the flux induced in said audio transformer by the flux of said supply transformer is neutralized by the flux from said coil.
11. In a radio receiver unit, the combination of a chassis, an alternating current energy supply transformer mounted on said chassis, a plurality of vacuum tubes and associated circuits carried by said chassis and forming a radio receiver, including an audio frequency amplifying system, including an audio frequency transformer, and a coil having substantially the same flux variation characteristics as said supply transformer series related in the filament heating circuit of at least one of said tubes and located in close proximity to said audio transformer with an orientation with respect to said audio transformer by which the flux induced in said audio transformer by the flux of said supply transformer is neutralized by the flux from said coil.
12. In an amplifying system the combination of a chassis, an alternating current energy supply transformer mounted upon said chassis, an audio frequency transformer forming part of an amplifying system carried by said chassis, and means including a reactance connected with the primary of the supply transformer for neutralizing the flux induced in said audio transformer by said supply transformer.
13. In an amplifying system the combination of a chassis, an alternating current energy supply transformer mounted upon said chassis, an audio frequency transformer forming part of an amplifying system carried by said chassis, and means including an inductance connected across the primary of the supply transformer for neutralizing the flux induced in said audio transformer by said supply transformer.
14. In an amplifying system the combination of a chassis, an alternating current energy supply transformer mounted upon said chassis, an audio frequency transformer forming part of an amplifying system car-

ried by said chassis, and means including a reactance connected in the secondary circuit of the supply transformer for neutralizing the flux induced in said audio transformer by said supply transformer.

15. In an amplifying system the combination of a chassis, an alternating current energy supply transformer mounted upon said chassis, an audio frequency transformer forming part of an amplifying system carried by said chassis, and means including an inductance connected in the secondary circuit of the supply transformer for neutralizing the flux induced in said audio transformer by said supply transformer.

16. In an amplifying system the combination of a chassis, an alternating current energy supply transformer mounted upon said chassis, an audio frequency transformer forming part of an amplifying system carried by said chassis, and an impedance connected with said supply transformer and in close proximity to said audio transformer for neutralizing the flux induced in said audio transformer by said supply transformer.

In witness whereof, I have hereunto subscribed my name this 17th day of July 1929.

BENJAMIN F. MIESSNER.
